His Attorney.

UNITED STATES PATENT OFFICE.

JOHN F. MORGAL, OF CLEVELAND, OHIO, ASSIGNOR TO ELECTRIC VACUUM CLEANER COMPANY, INC., OF CLEVELAND, OHIO, A CORPORATION OF NEW YORK.

VACUUM CLEANER.

Application filed September 13, 1927. Serial No. 219,830.

The present invention relates to vacuum cleaners and especially to vacuum cleaners of the portable type and which comprise a suction nozzle and a power driven means for creating the suction in the nozzle.

In connection with such cleaners, it is desirable to provide in the suction nozzle a means which operates on the surface of the rug or carpet to disturb the nap of the rug or carpet so as to loosen the particles of dirt and other foreign matter embedded therein to enable the suction to draw out such particles.

The object of my invention is to provide an improved construction and arrangement for operating on the nap of a rug or carpet for spreading the nap and thereby loosening the dirt so as to enable the same to be picked up by the suction of the cleaner, and for a consideration of what I believe to be novel and my invention attention is directed to the following specification and the claims appended thereto.

In the drawing, Fig. 1 is a perspective view with parts broken away, of a vacuum cleaner embodying my invention; Fig. 2 is a section taken on line 2—2, Fig. 1; Fig. 3 is a detail perspective view of a modification; Fig. 4 is a detail perspective view of a further modification; and Fig. 5 is a detail perspective view of another modification.

In the drawing, I have illustrated my invention as applied to vacuum cleaners of the electric motor driven type. It is to be understood, however, that the invention is not limited necessarily to this type of cleaner although it is especially adapted for use in connection with such type.

Referring to the drawing, 1 indicates the electric motor of a vacuum cleaner; 2 indicates the fan casing; 3 indicates the suction fan carried by the shaft of motor 1; 4 indicates the suction nozzle; 5 indicates the dust bag; and 6' indicates the handle of a vacuum cleaner. The type of cleaner indicated is a known one, and its specific construction as so far described forms no part of my present invention. It is to be taken as typical of any suitable vacuum cleaner which comprises a suction nozzle and a suction producing means.

According to my invention, I provide in the suction nozzle of the vacuum cleaner an agitating means for the nap of the rug or carpet which agitating means moves lon-

gitudinally of the nozzle, the movement thereof being effected preferably by the mechanism which drives the suction creating means. Such agitating means forms in substance a separator for separating or spreading apart the fibres forming the nap of the rug or carpet and may take various forms and may be arranged to move in various ways.

In Figs. 1 and 2 I have illustrated an embodiment of the invention wherein the agitating means comprises an endless belt 6 upon which projecting elements 7 are fastened by suitable means such as rivets. The projecting elements may take various forms. Preferably, I form them from sheet metal of suitable thickness, the metal being stamped up to provide a central portion for attachment to the endless belt 6 and one or more outwardly projecting parts. The endless belt 6 is mounted on suitable guide rollers 8 arranged in the suction opening of the cleaner and extends up over a pulley 9 mounted on the end of the shaft of motor 1. The pulley 9 serves to drive the endless belt, and the guide rollers 8 serve to cause the belt to travel in a straight line longitudinally of the suction nozzle opening, the guide rollers being located in a straight line just above the plane of the mouth of the suction opening.

The rollers 8 are located so that the agitating devices 7 will engage the rug or carpet and disturb the nap of the same.

As is known in connection with the operation of vacuum cleaners, the suction of the cleaner serves to lift the rug or carpet up toward the nozzle opening whereby the opening is sealed. The suction then serves to draw air up through the rug or carpet, the air carrying with it the dust particles and other foreign matter in the rug or carpet. The projections 7, in the moving across the surface of the rug or carpet scrape the same and serve to separate the fibres of the nap, thus loosening even deep seated particles and effecting their removal.

In Fig. 3 is illustrated an arrangement wherein the endless belt is in the form of a chain 10 driven by a spur wheel 11 on the end of the motor shaft. The chain is provided with attachment links 12 to which separators or agitators 13 are attached by rivets 14. This arrangement provides a positive drive for the belt.

In Fig. 4 is illustrated an arrangement wherein an endless belt 15 is formed from rubber and has teeth 16 moulded on its inner surface for engagement with a pinion 17 on the motor shaft. Pinion 17 may be formed of metal. On belt 15 are metal agitators or separators 18 and between them are arranged brush members 19.

In Fig. 5 is an arrangement similar to that shown in Fig. 4 except that the brush members 20 are vulcanized to the endless belt 21.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. The combination with a vacuum cleaner having a suction nozzle and a motor the shaft of which projects into said nozzle, of an endless carrier in the nozzle which carrier extends over said shaft and is moved longitudinally of the nozzle by said motor, and nap disturbing and separating means carried by said carrier.

2. The combination with a vacuum cleaner having a nozzle, a fan and a motor for driving the fan, of guide roller means located adjacent to the plane of the mouth of the nozzle, a belt on said guide roller means, nap agitating and separating means carried by said belt, and means for driving the belt from said motor.

In witness whereof, I have hereto set my hand this 9th day of September, 1928.

JOHN F. MORGAL.
